G. M. WUTZLER

COAL SPOUT OPERATING DEVICE

Filed Jan. 29, 1925

INVENTOR

G. M. WUTZLER
BY Munn & Co.

ATTORNEYS

UNITED STATES PATENT OFFICE.

GEORGE M. WUTZLER, OF WAUKEGAN, ILLINOIS.

COAL-SPOUT-OPERATING DEVICE.

Application filed January 29, 1925. Serial No. 5,614.

My invention relates to improvements in coal spout operating devices, such as intended for use with continuous stokers, and it consists in the combinations, constructions, and arrangements herein described and claimed.

An object of my invention is to provide a device of the character described which automatically moves the down spout of a 10 coal bunker through an oscillatory path over the feeder trough of a boiler, furnace, or the like.

A further object of my invention is to provide a device of the character described 15 in which the working parts are protected from unintentional engagement with falling pieces of coal or the like, and in which the covering also serves to shelter the lubricated working parts, which otherwise would be 20 come covered with a deposit of coal dust.

A further object of my invention is to provide a device of the character described which is entirely automatic in its operation, which is compact in form, and which is 25 thoroughly practical for the purpose intended.

A further object of my invention is to provide a device of the character described which may be readily disconnected from 30 the spout as in manual operation of the spout.

Other objects and advantages will appear in the following specification, and the novel features of the invention will be particularly 35 pointed out in the appended claims.

My invention is illustrated in the accompanying drawings forming part of this application, in which

Figure 1 is a sectional view of an embodiment of my invention,

Figure 2 is a front elevation of the mechanism partially illustrated in Figure 1, and

Figure 3 is a front elevation of a part of the mechanism illustrated in Figure 2.

In carrying out my invention I make use 45 of the ordinary type of boiler such as used in power plants, heating plants, and the like. I have shown a portion of the front portion of the boiler in dotted lines in Figure 1. Means for guiding coal and fuel, usually to a moving grate or feeding trough, is provided in a down spout 2 of ordinary construction which is adapted to swing back and forth across the feed trough or moving 50 grate. This is well known in the art and needs no further explanation.

My invention pertains to an automatic means for swinging the spout 2 through an oscillatory path over the trough or moving 60 grate.

The device consists in a spout engaging member 3 which is substantially semi-annular in contour so as to partially encompass the side walls of the spout 2. This member 3 has a neck 4 and a substantially 65 vertical flattened portion 5. The member 3 is pivotally mounted by means of a bolt 6 to members 7 carried by a carriage 8.

The carriage 8 consists in a substantially 70 vertical plate 9 having four wheels 10 rotatably mounted in turn in the same plane with the plate 9.

The wheels 10 are arranged to bear upon parallel horizontal side walls 11 of an elongated casing 12. This casing 12 is open at 75 each end and is secured by means of bolts 13 to the front panel 1 of the boiler.

The casing 12 is formed with its side walls 11 bent toward one another at 14 to form front wall portions 15 of the casing 80 which lie in the same plane and are parallel to the rear wall of the casing. Four wheels 18 are rotatably mounted upon the plate 8 and are arranged to bear and ride upon the inner surface of the wall portions 15. Thus the wheels 10 and 18 serve as a guide and movable support by means of which the carriage 8 may move with a reciprocating movement in the casing 12.

A return lead screw 20 is rotatably mounted in the casing 12 by means of bearing members 21. This lead screw 20 has a portion 22' which is adapted for engagement with a gear, pulley, or the like for connection with a source of power, such as an electric motor, steam engine, or other driving means.

Referring now to Figure 3 it will be noted that the return lead screw 20 has both left and right hand threads cut therein. Thus 100 a member such as the bifurcated engaging member 22 when placed in engagement with the threads of the screw 20 will move to and fro along the screw as it is rotated.

The member 22 is secured to the plate 9, thereby causing a longitudinal, reciprocating movement of the plate when the screw is rotated.

In order to maintain the engaging member 22 in proper engagement with the threads 110 of the screw 20 I provide a guide roller 24 which is rotatably mounted upon rearwardly

extending plates 25 carried by the plate 9 and which engage with that portion of the screw 20 diametrically opposite to the engaging member 22.

5 From the foregoing description of the various parts of the device, the operation thereof may be readily understood. Only one means of motive power is connected to the screw 20 at the portion 22' so that the 10 screw 20 is constantly driven.

As soon as the engaging member 22 is in engagement with the return threads of the screw, the entire carriage 8 to which the engaging member is secured will move from 15 one end of the screw 20 to the other upon its threaded portion.

The engaging member 22 will be held in proper engagement with the screw 20 by 20 means of the guide roller 24 so that the engaging member may not abuse or mutilate the threads.

Friction between the carriage and the casing 11 is reduced to a minimum by virtue of 25 the wheels 10 and 18 which permit the carriage to move easily from one end of the screw threads to the other within the casing 12.

The bifurcated member 3 which is in engagement with the spout 2 will cause the 30 spout to move through an oscillatory path and thus deliver coal or the like which is passed therethrough from the upper end to any suitable feed trough, grate, or the like such as found in boilers and furnaces of 35 ordinary construction. It should also be

noted from Figure 1 that the wheels 10 and 18 and the guide rollers 24 bear against the inner surfaces of the casing 12, thus preventing accidental movement while guiding the spout 2 in its travel. The casing 12 40 also shields the working parts from foreign matter. It is obvious that a large guiding surface must be provided for the spout 2 for taking up side thrust of the spout, due to strains from the falling coal. The inner 45 surfaces of the casing 12 accomplish this purpose.

I claim:

1. The combination with a movable coal spout, of a carriage loosely connected to said spout and having wheels, means for reciprocating said carriage, an elongated casing enclosing said carriage and said reciprocating means, said casing having walls whose inner surfaces are adapted to guide said wheels. 50

2. The combination with a movable coal spout, of a carriage loosely connected to said spout and having wheels for supporting the weight of the carriage, auxiliary guide wheels disposed at right angles thereto, 60 means for reciprocating said carriage, and a casing enclosing said carriage and said reciprocating means, said first named wheels being arranged to bear on said casing for supporting the greater weight of the carriage, 65 and said guide wheels being arranged to engage the inner walls of the casing for guiding the carriage in its movement.

GEORGE M. WUTZLER.
